VACUUM CLEANER WITH MOP CLEANING
RECEPTACLE

Sherman F. Wells, Minneapolis, Minn.

Application December 2, 1940, Serial No. 368,121

7 Claims.

(Cl. 15—9)

My present invention relates to vacuum cleaners and is in the nature of a modification of or improvement on the vacuum cleaner with auxiliary mop cleaning attachment disclosed and claimed in my prior Patent No. 2,219,911 of date October 29, 1940.

In the present improved device the mop receptacle is in the nature of an open pan or pocket formed as a part of the dust-receiving bag and having connections whereby, under proper adjustment of valve mechanism, the dust or lint from the mop will be drawn from the mop receptacle through the fan or blower and delivered into the dust bag. Under other proper adjustments of the valve mechanism, the vacuum cleaner may be used in various different ways, for example, to pick up dust or lint from the floor and deliver the same into the bag in the customary way.

An improved and commercial form of the present invention is illustrated in the accompanying drawings, wherein like characters indicate like parts throughout the several views.

Referring to the drawings:

Fig. 1 is a view in perspective showing the complete device;

Fig. 2 is a fragmentary view in front elevation with some parts broken away and with some parts sectioned on the line 2—2 of Fig. 4;

Fig. 3 is a fragmentary front elevation of the device showing especially the pick-up nozzle and valve-actuating device;

Fig. 4 is a side elevation of the complete device, some parts being broken away and some parts being sectioned; and

Fig. 5 is a vertical section taken approximately on the line 5—5 of Fig. 1.

My invention is capable of being incorporated in connection with vacuum cleaners of various different designs but, as shown, is applied to a vacuum cleaner in which the head or body of the cleaner involves a motor casing 10, a fan casing 11, and a pick-up nozzle 12, said device being adapted to ride upon wheel-equipped arms 13 shown as attached to the motor casing 10. Preferably, the elements 10, 11 and 12 will be separately made but rigidly connected.

Working within the fan casing 11 is a fan 14 secured on a shaft 15 journaled in the front wall of the motor casing 10 and connected to and driven by the motor, not shown, but which, in the type of vacuum cleaner illustrated, is located in the motor casing 10. The fan casing 11 has an axial air intake passage 16.

Mounted in the head of the pick-up nozzle 12

is a rotary cup-shaped valve 17 that is provided with an axial shaft or stem 18 that extends to the exterior of the head of the pick-up nozzle and, in the preferred construction illustrated, is provided with a rigidly secured arm 19. The open end of this rotary cup-shaped valve 17 registers with and is in constant communication with the eye 16 of the fan casing 11. The rotary or oscillatory valve 17 is provided with a single axial air intake port 20, see particularly Figs. 2 and 5, that normally registers with a port 21 in that portion of the head of the pick-up nozzle that constitutes a seat for the valve 17. That portion of the head of the pick-up nozzle that constitutes a seat for the valve 17 has a tubular extension 22 that is normally closed by the valve but is adapted to be opened when the valve is rotated about 90° or far enough to bring the valve port 20 into registration with said tubular extension 22 and at the same time to close the port 21 that leads from the nozzle to the interior of the valve.

The main receptacle or dust bag proper, indicated at 23, is of the usual flexible material that is impervious to the passage of dust, but will permit the escape of air as is customary in vacuum cleaners.

The fan casing 11 has a tangential or peripheral discharge neck or nozzle 24 to which the bag 23 is adapted to be connected by a coupling 25, preferably such as usually employed. In its upper or extended end the bag 23 is formed with a mop receptacle preferably a dish-like structure or depression formed by a dished diaphragm 26 which, at its contracted bottom, is provided with an inset quite coarse mesh wire screen 27. The diaphragm 26 is preferably of quite stiff rubber but should be of some material that is impervious to the passage of air, so that under air pressure from within the bag there will be no escape of air through said diaphragm.

Within the bag 23 is a suction pipe 28, preferably a rubber tube, having a flaring receiving end 29 that is vulcanized or otherwise rigidly secured to the diaphragm just radially outward of the screen 27. At its delivery end the tube 28 is extended to the exterior of the bag 23 and by a coupling 30 is connected to the receiving end of the tubular extension 22. The vacuum cleaner shown is provided with the customary handle bar 31, the forked end 32 of which is pivotally connected to the head or body portion of the vacuum cleaner, the said prongs, as shown, being pivotally connected to the tubular extensions 22 and 24. The upper end of the bag 23 is conveniently

hung from the upper end of the handle bar 31 by suitable means such as a hanger strap 33.

In this preferred arrangement, the oscillatory valve 17 is, as already indicated, normally held in the position shown in Figs. 2 and 5; and this is shown as accomplished by torsion spring 34 anchored to the head of the intake nozzle and to the valve stem 18. Said valve stem 18, at its extended end, is provided with a short arm or lever 35 provided on its hub with a lock lug or shoulder 36 which, when said lever is depressed, will be engaged by a spring-pressed latch dog 37 pivoted at 38 to the head of the pick-up nozzle.

When lever 35 is depressed and held by latch dog 37, valve 17 will be moved so as to close the port 21 of the intake nozzle and open communication between valve port 20 and the tubular extension 22, thereby connecting the suction pipe 28 to the fan. Of course, the open end of valve 17 will always be in communication with the eye 16 of the fan casing 11.

An ordinary dust mop is in Fig. 4 and is indicated by the character A. When the intake of the fan is connected to the suction tube 28 and a mop is placed in the mop receptacle 26, and especially when the mop is rubbed or moved over the screen 27, not only dust but the lint from the mop will be drawn into the suction tube and from thence will be carried to the motor-driven fan and from thence blown into the bag 23. To briefly summarize the above operation when valve 17 is in so-called normal position indicated in Fig. 2, dust will be picked up from the pick-up nozzle and delivered into the fan and when said valve is moved to the position just above noted and latched in that position by the dog 37, dust will be drawn from the mop receptacle and the mop and delivered into the bag. When the valve has been latched in the position last noted and is desired to return the valve to its normal position, it is only necessary to press upon the latch dog and thereby permit the torsion spring 34 to quickly restore the valve to its normal position first noted.

The above described latch mechanism is very convenient and desirable but, of course, the valve can be otherwise moved and otherwise held in whichever of the two positions it is adapted to be set.

In Fig. 4, the bag 23 is shown as provided with a clean-out opening normally closed by a plate or closure 39.

It is important to note that in this present embodiment of my invention, a single valve serves to form all of the valve opening and closing movements necessary to convert the machine from one that picks up dust or dirt from its pick-up nozzle or from the mop receptacle. Also this is accomplished by a valve of novel construction, the interior of which is always open to the source of partial vacuum, to wit: the motor-driven fan or blower.

In the device of this application the mop receptacle 26 forms a part, to wit: as shown, the upper end of the dust bag and the concave or depressed outer surface of this receptacle is normally exposed for ready insertion of the mop and removal therefrom. Also, as stated, the diaphragm 26 is preferably quite stiff so that it will give form to the upper end of the bag.

Also, it will be understood that while I have illustrated and described a preferred embodiment of the invention, that various modifications

thereof may be made within the scope of the invention herein disclosed and claimed.

What I claim is:

1. In a vacuum cleaner, a fan casing and a rotary fan therein, a pick-up nozzle having a delivery conduit leading to the intake of said fan casing, a dust-collecting bag connected to the outlet of said fan casing, a mop receptacle formed as a part of the outer wall of said bag and exposed at the exterior thereof for the insertion of a mop, a dust delivery conduit leading from said mop receptacle to the intake of said fan casing, and valve mechanism constructed and arranged, in one position, to simultaneously open the delivery conduit of said nozzle and close the delivery conduit of said mop receptacle, and in another position, to simultaneously open the delivery conduit of said mop receptacle and close the delivery conduit of said nozzle.
2. The structure defined in claim 1 in which said dust delivery conduit from said mop receptacle is a tube extended therefrom through said bag and to the exterior thereof where its connection to the intake of said fan casing is made.
3. The structure defined in claim 1 in which said mop receptacle is a depressed concave diaphragm forming a part of the upper wall of said bag and provided, in its bottom, with a screen, said dust delivery conduit being a tube, the upper end of which is attached to the bottom of said mop receptacle radially outward of said screen.
4. In a vacuum cleaner, a fan casing and a rotary fan therein, a pick-up nozzle having a delivery conduit leading to the intake of said fan casing, said fan casing having two like projections, one of which extends from the outlet of said fan casing, and the other of which is connected to the intake of said fan casing, a dust-collecting bag connected to the first of said tubular extensions, a dust delivery tube connected to the second of said tubular extensions, said bag, at one end, having a concave mop receptacle formed as a part of the outer wall thereof and exposed at the exterior of said bag, said dust delivery tube, at its receiving end, being connected to the bottom of said mop receptacle, and valve mechanism constructed and arranged, in one position, to simultaneously open the delivery conduit of said nozzle and close the delivery conduit of said mop receptacle, and in another position, to simultaneously open the delivery conduit of said mop receptacle and close the delivery conduit of said nozzle.
5. In a vacuum cleaner, a fan casing and a rotary fan therein, a pick-up nozzle having a delivery conduit leading to the intake of said fan casing, said fan casing having two like projections, one of which extends from the outlet of said fan casing, and the other of which is connected to the intake of said fan casing, a dust-collecting bag connected to the first of said tubular extensions, a dust delivery tube connected to the second of said tubular extensions, said bag, at one end, having a concave mop receptacle formed as a part of the outer wall thereof and exposed at the exterior of said bag, said dust delivery tube, at its receiving end, being connected to the bottom of said mop receptacle, and a cup-shaped rotary valve mounted in the connection between said nozzle and intake of said fan casing with its open end in constant communication with said fan casing, said valve having a peripheral port which, under rotary adjustments of said valve, in one position, will simultaneously open the delivery conduit of said

nozzle and close the delivery conduit from said mop receptacle, and in another position, will simultaneously open the delivery conduit of said mop receptacle and close the delivery conduit of said nozzle.

6. The structure defined in claim 1 in which said valve mechanism is a single cup-shaped oscillatory valve, the open end of which is in constant communication with the intake of said fan casing, said valve having a peripheral port which, under rotary movement of said valve, accomplishes the results stated, said cup-shaped valve hav-

ing an axially projecting stem equipped at its outer end with means for oscillating said valve, a spring tending to hold said valve in normal position, and a releasable latch for securing the said valve in its other operative position.

7. The structure defined in claim 1 in further combination with yielding means tending to hold said valve mechanism in one of the positions indicated, and a releasable latch for securing said valve mechanism in the other indicated position.

SHERMAN F. WELLS.
